UNITED STATES PATENT OFFICE

2,453,487

SEALING MEANS FOR TRAVELING GRATE STOKERS

Royce L. Beers, Birmingham, Mich., assignor to Detroit Stoker Company, Monroe, Mich., a corporation of Michigan

Application February 16, 1945, Serial No. 578,169

2 Claims. (Cl. 110—40)

1

The invention relates to stokers of that type in which an endless grate travels forward from the bridge wall towards an ash discharge at the furnace front and fuel is deposited on said grate by an impeller fuel feeder or the like which projects the fuel from the front over the grate. Such construction is shown in my former patent, 2,302,173, of November 17, 1942. With such constructions the travelling grate separates the combustion chamber from an air pressure chamber therebeneath, which latter supplies air passing through apertures in the grate bars to support combustion of the fuel thereon. It is, therefore, important to maintain an air seal between the grate and the walls of the combustion chamber and more particularly between the portion of the grate entering said combustion chamber and the pressure air chamber therebeneath. Heretofore it has been the practice to extend the bridge wall over the portion of the grate passing upward about the supporting sprockets and also to place a series of tuyères in the angle between the front face of the bridge wall and the upper face of the grate. These tuyères permit a limited quantity of air to pass into the fuel at this point but prevent an unrestricted flow of air through the space between the grate bars and bridge wall. Inasmuch, however, as the upper portions of the grate bars are unmachined castings, it is difficult to maintain a joint between the same and the tuyères without interference with the travelling of the grate.

It is the object of the invention to obtain a construction which maintains a more effective seal between the grate and the pressure air chamber therebeneath which, at the same time, permits free movement of the grate without interference by such sealing means. To this end the invention consists in the construction as hereinafter set forth.

In the drawings:

Fig. 1 is a longitudinal section through a portion of the travelling grate including the portion passing upward around the sprockets adjacent to the bridge wall together with air sealing means;

Fig. 2 is a side elevation of one of the tuyères and the means for pivotally anchoring the same;

Fig. 3 is a plan view of Fig. 2;

Fig. 4 is a cross section on line 4—4, Fig. 3.

The specific construction of the travelling grate is not the subject matter of the instant invention but, in general, and as shown in Fig. 1 the grate travels towards the left away from the bridge wall and it comprises a series of cross

2

bars A, each pivotally connected to supporting chains and passing around sprockets B and horizontally over supporting rail C towards the furnace front. The sprockets for the upward moving portions of the chain are arranged adjacent to the bridge wall D which latter overhangs said sprockets and the portion of the chain passing therearound. There is also a segmental casting E which is sufficiently spaced from the grate bars passing about the sprockets to form an air channel for supplying air to the tuyères as hereinafter described. The casting E has at its upper end a hook portion E' for engaging the hooked rear ends F' of a series of tuyères F. The forward portions of these tuyères extend into the furnace chamber and rest upon the grate bars. Each tuyère is of inverted channel shape cross section having side flanges F² and a central rib F³. The forward end F⁴ is obliquely inclined and air ports F⁵ are formed therethrough to connect with the air spaces within the channel. The sides F² and rib F³ are also provided with an obliquely inclined cam portion F⁶ which will ride over any irregularity or projecting portion of the grate bar lifting the tuyère to avoid any obstruction to the movement of the grate. However, the forward portions F⁴ normally rest on the grate bars to form a substantial air seal therebetween so that the only escape for the air is through the ports F⁵.

The bridge wall D may be of any suitable construction but, as previously described, has a portion which overhangs the portion of the chain passing about the sprockets. This portion must provide sufficient clearance to permit the lifting of the tuyères when necessary but, at the same time, it is important to seal between the bridge wall and the tuyères so as to avoid leakage of air. This is accomplished by placing a flexible resilient material between the bridge wall and the tuyères, such as an asbestos packing G. With the construction described the pressure air beneath the grate is free to pass in the channel between the segmental member B and the chain into the air spaces within the hollow tuyères. From the latter the air will pass through the ports F⁵ in the front portion F⁴ and into the fuel lying adjacent thereto, assisting combustion and avoiding the piling up of fuel at this point. Each of the tuyère members is free to lift so as to ride over any projection in the portion of the grate bar therebeneath but normally all of these tuyères are in close proximity to the grate. It is necessary to occasionally renew tuyères. To permit of this, I have provided a

quick detachment connection with the casting E. This is preferably formed by a bar H which is inserted between the rear end of the hook portion F' and a shoulder H' on the member E. Thus, when a tuyère F is to be replaced, the packing G is first removed and the bar H lifted out of the recess, which will permit of disengaging the hooks F' and E' to free the tuyère.

While, as above stated, any suitable construction of bridge wall may be used, I have specifically illustrated a construction in which said bridge wall is supported by water tubes D' connected to a transversely extending header D². The packing G is supported by a plate D³ extending between the header D² and the segmental casting E and also extends forward of this plate over the tuyères F. As the packing G is flexible and yielding, it will not interfere with the rise of the tuyères F whenever this is occasioned by irregularities in the grate bars.

My invention is also applicable to stoker constructions where the tuyères between the bridge wall and grate are omitted but where there is still the necessity for forming an effective air seal. For such construction the pivoted member F does not constitute a tuyère but by resting on the grate bars seals off any air which might otherwise pass around with the sprockets and chain.

What I claim as my invention is:

1. In a stoker, the combination with a traveling grate and a furnace wall adjacent to one end thereof, of sealing means between said grate and furnace wall comprising a member pivotally anchored at one end and extending over said grate in the direction of travel thereof to rest thereupon, and a yieldable packing between said furnace wall and said member permitting movement of the latter to ride over any irregularity in the surface of the grate.

2. In a stoker, the combination with a traveling grate and a sprocket around which said grate

passes, of a segmental member passing about a portion of said sprocket and having a hooked end with a recess therein adjacent to said hook, a second member having a hooked end insertable through said recess into engagement with the aforesaid hooked end, said second member extending over said grate in the direction of travel thereof to rest thereupon, and a locking bar for engaging said recess to hold said hooks in engagement with each other while permitting the pivotal movement of said second member to ride over irregularities in the surface of the grate.
